UNITED STATES PATENT OFFICE.

ENOS FRANKLIN ARNOLD, OF LONG BEACH, CALIFORNIA.

INCLINOMETER.

Application filed January 8, 1926. Serial No. 80,078.

This invention relates to clinometers, particularly adapted for association with motor vehicles in order that the up or down grades of roads, upon which the so equipped vehicle is traveling, may be readily determined.

The primary object of the invention is to substantially improve, simplify, and reduce the cost of manufacture and sale of previously patented and used devices of this character.

Other objects will become apparent as the nature of the invention will be better understood, the same comprises the novel form, combination, and arrangement of parts hereinafter more fully described, shown in the accompanying drawing and claimed.

In the drawing forming part of this application, and in which like numerals designate like parts through the several views:

Figure 1 is a side elevation of my improved clinometer securing means;

Figure 2 is a view partly in elevation and partly in cross section showing the device as associated with a vehicle, one of the retaining plates of the clinometer being removed;

Figure 3 is a front elevation of the entire device;

Figure 4 is a front elevation of the clinometer gage per se; and

Figure 5 is a detail vertical cross section more clearly disclosing the shape of the gage member and the plate forming the retaining seat therefor.

Now having particular reference to the drawing, my novel clinometer constitutes the provision of a colored liquid carrying gage member 5 that is preferably of square shape as shown in Figure 2, and is of glass or other suitable transparent material. Said gage member consists of a marginal liquid receiving channel 6, and a central web portion 7 that forms square shaped depressions 8-8 upon opposite sides of the gage member, Figure 5. The liquid receiving channel 6 is formed at its top edge with a filler opening 10 that is normally closed with a cap 11 in order that the supply of fluid within the channel of the gage member may be removed or replenished as desired.

Adapted to be secured in a suitable manner to the forward side of the liquid carrying gage member 5 is a gage plate 9 formed centrally with a vertical slot 9' at opposite sides of which and at opposite ends are

graduation marks starting from the center of the plate as clearly shown in Figure 4.

The gage member 5 is secured between a pair of relatively square shape metallical plates 12-12 that are formed with central depressions 13-13 for interfitting relation with the depressions 8-8 of said gage member, Figure 5, in order that the gage member will not move therebetween. The upper and lower edges of these plates extend above the respective edges of the gage member and are interconnected through the medium of bolt and nut fasteners 14.

At the forward ends of said plate 12-12 outwardly extending wings 15-15 are provided, each of which is provided centrally with an opening 16 in order that an oval shaped front cover plate 17 may be secured thereto. This plate 17 is also formed with an outwardly bulged portion 18 which has set therein a strip of glass 19 that is supported by and insulated from the front side of the gage by an oval shaped packing strip 20, Figure 2.

Said assembled clinometer is adapted to be disposed through an opening *a* in the instrument board A of a motor vehicle and there secured by reason of bolt and nut connections 21 between the plate 17 and said instrument board, also clearly shown in said Figure 2.

It is of course to be understood that the gage member 5 is to be exactly one-half filled with liquid and when the machine is upon an exactly level road, the fluid will be entirely within the lower half of the gage member.

However, should an upgrade or downgrade in the road be reached, the liquid in the forward portion of the channel 6 will rise or fall, and indicate the inclination by reason of the graduations upon the plate 9, it being obvious that said bulged portion 18 of the member 17 is formed centrally with an opening 23 for allowing the graduations upon the plate to be properly viewed.

Accordingly, it will be appreciated that I have provided a highly novel, simple, and relative inexpensive form of clinometer for motor vehicles that is well adapted for all the purposes designated.

Having thus described my invention, what I claim as new and desire to secure by Letters Patent is—

1. In an clinometer of the class described adapted to be supported within an

opening of a vehicle instrument board, a relatively square shaped transparent vessel including a central web portion and a marginal liquid channel for providing depressions upon the opposite sides of the vessel, said vessel being partly filled with a liquid, a pair of plate members adapted to be supported upon the opposite sides of the vessel and having depressions therein for interfitting relation with the depressions of the vessel, and graduations upon the front side of the vessel whereby the inclination may be ascertained by reason of the rise or fall of the liquid within the forward side of the marginal channel.

2. In an inclinometer of the class described adapted to be supported within an opening of a vehicle instrument board, a relatively square shaped transparent vessel

including a central web portion and a marginal liquid channel for providing depressions upon the opposite sides of the vessel, said vessel being half filled with a colored liquid, a pair of plate members adapted to be supported upon the opposite sides of the vessel and having depressions formed therein for interfitting relation with the depressions of the vessel, graduations upon the front side of the vessel whereby the inclination may be ascertained by reason of the rise or fall of the liquid within the forward side of the marginal channel, and means carried by the forward edges of the plates whereby the inclinometer may be secured within the opening of the instrument board.

In testimony whereof I affix my signature.

ENOS FRANKLIN ARNOLD.
